ABRASIVE APPLYING MACHINE

Owen Doutt, Detroit, Mich., assignor to General Spring Bumper Corporation, Detroit, Mich., a corporation of Michigan

Application February 14, 1930. Serial No. 428,309

30 Claims. (Cl. 91—47)

This invention relates to a machine adapted to be used in applying abrasive to the periphery of grinding wheels. Grinding wheels of the type in connection with which this machine is to be used are employed in finishing bumper bars and analogous uses. In preparing the wheels for use they are first coated with glue or other suitable adhesive material and then pounded into a receptacle containing the abrasive material. Usually 5 a number of coats of the abrasive material are applied, but this is optional. After the wheels are coated, they are used for grinding purposes until the abrasive material is worn off or dislodged, after which they may be again coated 10 by a process involving the use of the machine which embodies this invention.

It has been found in practice that the most desirable method of applying the abrasive material is by pounding the periphery of the glue-coated wheel into a mass of the abrasive. Accordingly, the principal object of this invention is to provide a machine which shall carry the grinding wheels and impart to them a motion with respect to a receptacle of abrasive material 25 which shall result in pounding the periphery of the wheel into such material.

A further object is to provide a machine for accomplishing this general purpose which shall be convenient in use, enabling larger production 30 per man to be secured (about three times that of a man operating without the assistance of a machine) and to secure an assembly which shall be sturdy and durable. Other and more specific objects will become apparent from the following 35 description.

Referring to the drawings, Fig. 1 is a side elevation of a machine embodying my invention; Fig. 2 is a front elevation of the same showing certain parts omitted; and Fig. 3 is a top plan 40 view thereof.

I have shown in the drawings a machine including a suitable frame designated generally by the numeral 10, and embodying upright members, suitable bracing members, a floor 11 adapted 45 to support a receptacle 12 containing abrasive material, and a floor 13 upon which may be mounted a driving motor 14. Mounted on the frame member 15 are bearing members 16 in which is journaled a shaft 17. The shaft 17 carries centrally thereof a pinion 18 and at one end a pulley 19 which is connected to the pulley 20 of the motor 14 by means of a belt 21.

Also carried by the member 15 is a block 23 secured by bolts 24 and carrying a pair of bearing members 25. Mounted in the bearing members

25 is a crank shaft 26 which carries centrally thereof a gear 27 meshing with the pinion 18 and carrying at the ends crank portions 28.

A pair of rocker arms 29 are pivotally connected to the crank pins 28 by means of bearing members 30 attached to said rocker arms. A pair of rods 31 are pivotally connected centrally to the rocker arm as at 32 by means of bolts 33 carried by said rocker arms and forming with the upper portions 34 of the rods 31 suitable bearing members. It is to be understood that suitable grease cups will be provided in connection with the upper ends 34 whereby these bearings may be kept lubricated both for the purpose of preventing friction and also for keeping the bearings flushed 60 with grease to prevent the abrasive material from working into them.

The rocker arms 29 are connected by means of a U-shaped member 36 which has the legs thereof spaced a sufficient distance to allow the wheels 75 to be introduced therebetween. On each leg of the U-shaped member is carried a guiding finger 37 which is adapted to contact with the sides of the wheel 38 to hold the same centrally disposed. Carried on the upper surfaces of the rocker 80 arms 29 I provide an arbor receiving means which consists of the member 40 and a resilient spring member 41 on each said arm carrying at its outer end a conically pointed retaining member 42 secured by means of a nut 43. The member 40 is 85 provided with a recess at one end thereof to receive a portion of the member 42. The member 42 is made of hardened steel to prevent its wearing away rapidly because of the presence of the abrasive material, some of which inevitably finds 90 its way into this mechanism. It will be evident by referring to Fig. 1 that the arbor 45 can be introduced by simply thrusting the same between the upper portion of the rocker arm and the point of the member 42, the conical face thereof acting 95 as a cam to cause flexing of the member 41 and also that a similar camming action on the opposite face of the member 42 may be relied upon for withdrawing the arbor from the retaining means.

Pivoted on the frame 10 at 46 is a lever 47 which carries a cross member 48. The levers 47 are provided with openings to receive the lower ends of the rods 31, which rods are provided with collars 49 thereon to constrain motion in a downward direction.

Attached to the front frame members 10 are plates 50 which have notches 5 in the edge thereof to receive a cross rod 52 upon which the front ends of the levers 47 are adapted to rest. Pivoted 105

at 52^a on the frame is a foot lever 53 connected by means of a link 54 to the lever 47.

The dotted line A is a portion of the envelope of the positions of the periphery of the wheel 38, that is the locus of a point thereof moving in the receptacle 12.

In the operation of this machine, the arbor 45 carrying the wheel 38, properly glued, is thrust between the upper surface of the rocker arms 29 and the members 42 and held thereby in firm position while the wheel is moved by means of the levers described, driven through the crank shaft by means of the motor, in such a manner as to give a pounding action to the wheel, which action results in embedding the abrasive material in the glue in such a way that the same is firmly held and gives long grinding wear as compared with methods of applying the abrasive which do not involve the pounding action, insofar as I am aware. When it is desired to insert the wheel, the operator steps on the foot lever 53, which results in elevating the rod 31 and consequently the rocker arms 29 to a position in which the wheel may be inserted without any interference from the abrasive material in the receptacle 12. The adjusting slots 51, as well as the adjustable feature of the collar 49, provide for adjustment to accommodate wheels of different sizes and to vary the force of the pounding blow. It has been found in practice, after considerable experimentation, that the pounding action of this machine serves to embed the abrasive particles in the glue so thoroughly that the same are in many cases more than two-thirds covered by a closely adhering coating of glue and this, of course, results in increased adhesion of the abrasive particles to the wheel.

It will be apparent from the foregoing that I have provided an abrasive applying machine which is well adapted for its intended purpose, and while I have illustrated one embodiment thereof, it is evident that my invention in its broader aspects may be carried out in a number of variant forms, and I wish to be limited only in accordance with the scope of the appended claims and the requirements of the prior art.

Having thus described my invention, what I claim is:

1. A machine for applying abrasive to a grinding wheel, said machine including means for supporting said wheel with respect to a mass of abrasive material, means for holding said abrasive material, and means for giving to said supporting means such a motion with respect thereto that the periphery of said wheel is pounded into such abrasive material and given a rolling motion.

2. A machine for applying abrasive to a grinding wheel, said machine including means for freely, rotatably supporting said wheel with respect to a mass of abrasive material, means for holding said abrasive material, and means for giving to said supporting means such a motion with respect thereto that the periphery of said wheel is pounded into such abrasive material and given a rolling motion.

3. In a machine for applying an abrasive to a glue coated grinding wheel, a frame, a crank mounted on said frame, motor means for driving said crank, a rocker arm connected to said crank, a supporting bar pivoted to said rocker arm at a point spaced from the point of connection of said crank, means for constraining the motion of said bar with respect to said frame, and means carried by said arm for receiving an arbor of a grinding wheel.

4. In a machine for applying abrasive to a glue coated grinding wheel, a frame, a shaft mounted on said frame, said shaft carrying spaced cranks, a pair of rocker arms pivoted on said cranks, means for constraining downward motion of each of said arms with respect to said frame, and means carried by said arms for receiving an arbor of a grinding wheel.

5. In a machine for applying abrasive to a glue coated grinding wheel, a frame, a shaft mounted on said frame, said shaft carrying spaced cranks, a pair of rocker arms pivoted on said cranks, means for constraining downward motion of each of said arms with respect to said frame, means carried by said arms for receiving an arbor of a grinding wheel, and a bar rigidly connecting said arms.

6. In a machine for applying abrasive to a glue coated grinding wheel, a frame, a shaft mounted on said frame, said shaft carrying spaced cranks, a pair of rocker arms pivoted on said cranks, means for constraining downward motion of each of said arms with respect to said frame, means carried by said arms for receiving an arbor of a grinding wheel, and a U-shaped bar rigidly connecting said arms.

7. In a machine for applying abrasive to a glue coated grinding wheel, a frame, a shaft mounted on said frame, said shaft carrying spaced cranks, a pair of rocker arms pivoted on said cranks, means for constraining downward motion of each of said arms with respect to said frame, means carried by said arms for receiving an arbor of a grinding wheel, a U-shaped bar rigidly connecting said arms, said U-shaped bar having the legs thereof spaced apart a distance greater than the thickness of the grinding wheel, and guiding fingers carried by said legs adapted to contact the sides of said wheel.

8. In a machine for applying abrasive to a glue coated grinding wheel, a frame, a shaft mounted on said frame, said shaft carrying spaced cranks, a pair of rocker arms pivoted on said cranks, means for constraining downward motion of each of said arms with respect to said frame, means carried by said arms for receiving an arbor of a grinding wheel, a U-shaped bar rigidly connecting said arms, said U-shaped bar having the legs thereof spaced apart a distance greater than the thickness of the grinding wheel, and resilient guiding fingers carried by said legs adapted to contact the sides of said wheel.

9. In a machine for applying an abrasive to a glue coated grinding wheel, a frame, a crank mounted on said frame, motor means for driving said crank, a rocker arm connected to said crank, a bar pivoted to said rocker arm at a point spaced from the point of connection of said crank, means for constraining the motion of said bar with respect to said frame, means carried by said arm for receiving an arbor of a grinding wheel, said constraining means including a lever mounted on said frame, and carrying means for receiving the lower end of said bar, said bar carrying a collar to cooperate with said last means.

10. In a machine for applying an abrasive to a glue coated grinding wheel, a frame, a crank mounted on said frame, motor means for driving said crank, a rocker arm connected to said crank, a bar pivoted to said rocker arm at a point spaced from the point of connection of said crank, means for constraining the motion of said bar with respect to said frame, means carried by said arm for receiving an arbor of a grinding wheel, said constraining means including a

- lever mounted on said frame, carrying means for receiving the lower end of said bar, said bar carrying a collar to cooperate with said last mentioned means, said lever being pivotally mounted at one end, and an adjustable stop for limiting its downward pivoting. 5
11. In a machine for applying an abrasive to a glue coated grinding wheel, a frame, a crank mounted on said frame, motor means for driving said crank, a rocker arm connected to said crank, a bar pivoted to said rocker arm at a point spaced from the point of connection of said crank, means for constraining the motion of said bar with respect to said frame, means carried by said arm for receiving an arbor of a grinding wheel, said constraining means including a lever mounted on said frame, carrying means for receiving the lower end of said bar, said bar carrying a collar to cooperate with said last mentioned means, said lever being pivotally mounted at one end, an adjustable stop for limiting its downward pivoting, and means pivotally mounted near the bottom of said frame and carrying means adapted to engage said lever to elevate same. 10
12. A machine for applying abrasive to a grinding wheel, said machine including means for supporting said wheel with respect to a mass of abrasive material, means for holding said abrasive material, and means for giving to said supporting means such a motion with respect thereto that the periphery of said wheel is pounded into such abrasive material. 15
13. The method of applying abrasive to a grinding wheel, comprising: coating the periphery of the wheel with a sticky substance and pounding at regular intervals contiguous portions of the periphery thus coated into a mass of abrasive material. 20
14. The method of applying abrasive to a grinding wheel, comprising: coating the periphery of the wheel with a sticky substance and pounding contiguous portions of the periphery thus coated into a mass of abrasive material at regular intervals with uniform pressure. 25
15. The method of applying abrasive to a grinding wheel, comprising: coating the periphery of the wheel with a sticky substance and intermittently contacting contiguous portions of the periphery thus coated with a mass of abrasive material with uniform pressure. 30
16. The method of applying abrasive to a grinding wheel, comprising: coating the periphery of the wheel with a sticky substance and rolling and pounding successive contiguous portions of the periphery thus coated into a mass of abrasive material with uniform pressure. 35
17. A machine for applying abrasive to a grinding wheel, said machine including means for holding a mass of abrasive material, means for supporting a grinding wheel in juxtaposition to the abrasive material, and instrumentalities for pounding the periphery of the wheel into the abrasive material. 40
18. A machine for applying abrasive to a grinding wheel, said machine including means for holding abrasive material, means for releasably and loosely holding a grinding wheel in juxtaposition to the abrasive material, whereby said wheel is freely rotatable relative to the holding means, and instrumentalities for pounding a portion of the periphery of the wheel into said material with a sweeping movement, whereby the material will cause said wheel to turn so that when the wheel is next presented a different por- 45
- tion of its periphery will be pounded into the material. 50
19. In a machine for applying an abrasive to a glue coated grinding wheel, a rocker, means for actuating said rocker, said rocker having means for holding a grinding wheel, and means for supporting a mass of abrasive material juxtaposed to the wheel thus held, whereby upon actuation of said rocker, the wheel will be pounded into the mass of abrasive material. 55
20. In a machine for applying an abrasive to a glue coated grinding wheel, a rocker, means for actuating said rocker, said rocker having means for holding a grinding wheel, and means for supporting a mass of abrasive material juxtaposed to the wheel thus held, whereby upon actuation of said rocker, the wheel will be pounded into the mass of abrasive material, the wheel being loosely carried by the rocker, whereby the wheel will be pounded into said material with a rolling action. 60
21. In a machine for applying an abrasive to a glue coated grinding wheel, a rocker, means for actuating said rocker, said rocker having means for holding a grinding wheel, and means for supporting a mass of abrasive material juxtaposed to the wheel thus held, whereby upon actuation of said rocker, the wheel will be pounded into the mass of abrasive material, a movable support for said rocker, and means for adjusting said support relative to said material to accommodate different sizes of grinding wheels to which said material is to be applied. 65
22. In a machine for applying an abrasive to a glue coated grinding wheel, a rocker, means for actuating said rocker, said rocker having means for holding a grinding wheel, and means for supporting a mass of abrasive material juxtaposed to the wheel thus held, whereby upon actuation of said rocker, the wheel will be pounded into the mass of abrasive material, and means for varying the relative position of said material and the grinding wheel, whereby said abrasive may be applied to different sizes of wheels and said material may be applied to wheels of the same size even though varying quantities of abrasive material may be employed. 70
23. In a machine for applying an abrasive to a glue coated grinding wheel, a rocker, means for actuating said rocker, said rocker having means for holding a grinding wheel, and means for supporting a mass of abrasive powder juxtaposed to the wheel thus held, whereby upon actuation of said rocker, the wheel will be pounded into the mass of abrasive powder. 75
24. In a machine of the class described, means for supporting a wheel to which abrasive material is to be applied, said means providing a bearing of substantially U-shape into and from which the arbor of the wheel may be freely inserted and removed, and resiliently mounted means engageable with said arbor to releasably hold the same in said bearing, said arbor serving to cam the last named means away from the path of movement of the arbor upon application of force on said arbor both in the direction of and away from said bearing, whereby said arbor may be snapped into and out of said bearing, and whereby said last named means will hold the arbor in its bearing against accidental removal. 80
25. In a machine for applying an abrasive to a glue coated grinding wheel, a rocker, means for actuating said rocker, said rocker having belt and gear means for holding a grinding wheel, and means for supporting a mass of abrasive ma- 85

- terial juxtaposed to the wheel thus held, whereby upon actuation of said rocker, the wheel will be pounded into the mass of abrasive material. 80
26. In a machine for applying an abrasive to a glue coated grinding wheel, a rocker, belt means for actuating said rocker, said rocker having means for holding a grinding wheel, and means for supporting a mass of abrasive material juxtaposed to the wheel thus held, whereby upon actuation of said rocker, the wheel will be pounded into the mass of abrasive material. 85
27. In a machine for applying an abrasive to a glue coated grinding wheel, a rocker, gear means for actuating said rocker, said rocker having means for holding a grinding wheel, and means for supporting a mass of abrasive material juxtaposed to the wheel thus held, whereby upon actuation of said rocker, the wheel will be pounded into the mass of abrasive material. 90
28. A machine for applying abrasive to a glue coated grinding element, said machine including means for holding a mass of abrasive material, a device for supporting a grinding element in operative relation to the abrasive material, means for shifting the element into an inoperative position to facilitate its removal and attachment of another element, and instrumentalities for pounding the periphery of the element into the abrasive material. 95
29. In a machine for applying abrasive material to a grinding element prepared to receive the same, a support for a grinding element, means for supporting a mass of abrasive material juxtaposed to the element thus supported, an oscillatory device supporting said support, and means for simultaneously oscillating said support and said device, whereby said element will be pounded into said material. 100
30. In a machine for applying an abrasive to a grinding element prepared to receive the same, a support for a grinding element, means for supporting a mass of abrasive material juxtaposed to the element thus supported, and instrumentalities for moving said element eccentrically and thereby causing portions of the element to intermittently contact said material. 105
